LABEL POCKET

Joel Hillman II, Harrison, and Morde M. Bloom, Rye, N.Y., assignors to Tension Envelope Corporation, Kansas City, Mo., a corporation of Delaware
Filed Jan. 27, 1964, Ser. No. 340,404
8 Claims. (Cl. 229—74)

This invention relates to a label which provides a pocket for containing an enclosure, such as an invoice, statement, and the like, pertaining to a mailing piece on which such label is attached.

A principal object of the invention is to provide a label of this character that may be produced inexpensively with standard envelope making machinery.

Other objects of the invention are to provide a label pocket construction which permits easy insertion of an enclosure prior to application of the label to a mailing piece; to provide a label pocket with upper and lower panels that are interconnected along two adjacent edge portions thereof to form an angular seat or stop to locate the enclosure and leave the opposite edges unconnected for facilitating insertion of the enclosure; to provide the upper panel of the label pocket with projecting portions that overlie edges of the lower panel to close said unconnected sides when the label is pasted onto a mailing piece; and to provide the upper panel with a window opening for exposing a mailing address on the enclosure.

When label pockets are applied to rather thick and rigid mailing pieces, they are difficult to open for removal of the enclosure because it is difficult to lift an opening flap or to get a letter opener or the like into the pocket without damaging the enclosure. Therefore, further objects of the invention are to cover the window opening by a patch having a portion capable of being seen through fixed to the inner face of the upper panel, and which has a loose gripping portion to facilitate grasping thereof for making an opening in the pocket as the side edges of the patch guide the lines of tear; and to provide the lower panel with an extension that underlies the gripping portion of the window patch to prevent sticking thereof to the mailing piece when paste or other adhesive is applied for securing the label to the mailing piece.

In accomplishing these and other objects of the invention, we have provided improved structure, the preferred forms of which are illustrated in the accompanying drawings, wherein:

FIG. 1 is a perspective view of the face side of a label pocket constructed in accordance with one form of the present invention, and showing attachment thereof to a mailing piece.

FIG. 2 is a similar view showing the manner in which the gripping portion of the window patch is pulled upwardly and backwardly longitudinally over the window opening, so that the side edges of the patch guide the lines of tear, thereby opening up a relatively wide opening across the face of the label to permit removal of the enclosure.

FIG. 3 is a plan view of the inner face of a blank from which the label pocket is folded, and showing the window patch applied thereto.

FIG. 4 is a plan view of the label pocket showing the back face thereof which is to be attached to a mailing piece by paste or other adhesive.

FIG. 5 is an enlarged perspective section of the label pocket, taken transversely through the window opening.

FIG. 6 is a similar section through the label pocket, but in a direction longitudinally through the window opening.

FIG. 7 is a plan view of the inside face of a blank for providing another form of the invention.

2

FIG. 8 is a perspective view of the label pocket form from the blank of FIG. 7, as viewed from the back face thereof, a portion of the panel being broken away to show the window patch.

FIG. 9 is a perspective view of the modified label pocket attached to a mailing piece.

FIG. 10 is a section of the line 10—10 of FIG. 9.

FIG. 11 is a section on the line 11—11 of FIG. 9.

Referring more in detail to the drawings, and first to the form of the invention illustrated in FIGS. 1 to 10 inclusive:

1 designates a label pocket constructed in accordance with the present invention and which is formed from blank 2, shown in FIG. 3. The blank 2 may be of envelope material and is divided by a line of fold 3 to provide generally rectangular panels 4 and 5 to overlie one another when the blank is folded on the fold 3. Extending from an edge of the panel 4 at the end of the line of fold 3 is flap 6, adapted to be folded on a line of fold 7 that substantially registers with the corresponding edge 8 of the panel 5. The flap 6 is to be secured to one or the other face of the panel 5 by an adhesive 9. The marginal portion 10 of the panel 4 that is directly opposite the flap 6 projects beyond the corresponding edge 11 of the panel 5. The remaining marginal edge of the panel 4 has spaced apart extensions 12 and 13 to provide a recess 14 therebetween, having a depth so that the inner edge 15 thereof preferably aligns with the adjacent end of the flap 6 at a corresponding end of the marginal portion 10. The panel 4 is provided in the body thereof with a window opening 16 in alignment with the recess 14 and spaced inwardly from the edge 15, to provide a portion 17 of the blank therebetween. The recess 14 is slightly greater in width than the adjacent end of the window opening 16. The blank 2 may have slits 18 and 19 that may extend inwardly from the terminals of the edge 15, for a purpose later described. The ends of the flap 6 and marginal extensions 10 and 12—13 preferably converge slightly at a join with connecting outer edges of the flap and extensions on curves 20. The junctures of the edge 15 of the recess 14 are also preferably curved, as indicated at 21.

In carrying out the invention, the window is covered with a patch 23 consisting of a material capable of being seen through and having greater tensile strength and durability than the material of the blank, so that the patch 23 may be used as a pull tab in tearing through the pane to which it is attached. The patch 23 is of greater length and height than the window opening 16, to provide a portion to be sealed over the window opening to the inner face of the panel 4 by an adhesive 24. The adhesive 24 may extend around the window opening 16, as indicated by dotted lines (FIG. 3). The end of the patch that is sealed to the portion 17 projects loosely across the recess 14 to provide a pull tab 25. The slits 18 and 19 preferably terminate near the longitudinal side edges 26 and 27 of the patch, and the adhesive 24 preferably terminates at the side of the slits 18 and 19, so that when the tab is pulled outwardly from the recess 14 the slits 18 and 19 start to tear which continue along the edges 26 and 27 of the patch when the label pocket is to be opened, as later described.

The back panel 5 is shaped at the edge thereof opposite the fold 3 so that the corners have notches 28 and 29 (FIGS. 3 and 4) to expose face portions of the extensions 12 and 13 of the panel 4, but the intermediate portion 30 covers the portion of the patch that provides the pull tab 25, to prevent any possibility of the paste or other adhesive that is used in attaching the completed label pocket to a mailing piece from contacting the pull tab 25. In order to further protect the pull tab, the outer edge thereof terminates short of the edge 32 of the portion 30.

be patch 23 may be cut and applied to the blank, the panel 5 folded over the front panel 4, and the flap folded over to be sealed with the adhesive 9 by means of standard envelope making machinery, to provide the pocket illustrated in FIG. 4.

will be noted that the product thus provided has a set 33 (FIGS. 5 and 6) closed at two sides by the 3 and 7 and open at the other two sides. The enclosure 34 to be inserted is pushed cornerwise through the 1 sides and seated squarely within the angle provided in the folds 3 and 7. When thus inserted, the entire 34 is completely contained under the back panel 5, indicated in dotted lines (FIG. 4), and the address 35 portion appears within the window opening 16 to serve as mailing address.

he label pockets as above described are supplied by the manufacturer to the user in the form shown in FIG. 4.

the label is furnished without adhesive on the back thereof, the user applies paste or other adhesive to the panel 5 of the label pocket so that the paste extends the projecting portions 10, 12 and 13 of the front panel 4. Then when the label pocket is placed upon the mailing piece 36 as shown in FIG. 1, the label pocket remains attached thereto. An alternate method of affixing the label pocket is to apply the paste to an area of the mailing piece 36 to be occupied by the label pocket, then the back of the label pocket is pressed therewith.

is obvious that the adhesive might be preapplied to label and dried during manfacture of the label, and if the label is to be used the adhesive is moistened to make it sufficiently tacky to stick to the mailing piece. The adhesive when applied in the manufacture of the label may be and remain tacky until used. Prior to use of the label the adhesive can be protected with a protective covering that can be peeled off just prior to use. The particular application and character of adhesive is a part of the invention.

hen the label is applied, the pocket 33 is securely
d to retain the enclosure 34 and without smearing
of with paste. The pull tab 25 also remains clean
free of paste because it is protected by the underlying
ision 30 of the back panel, as shown in FIGS. 4
6.

hen the mailing piece 36 is received by the addressee, enclosure 35 is easily removed by grasping the loose portion 25 of the patch 23 between the thumb and finger and pulling it upwardly within the recess 14, to e the slits 18 and 19 to start tears along the side s 26 and 27 of the patch. The pull on the tab 25 is inued toward the opposite side of the label pocket, own in FIG. 2, with the side edges of the patch con-
ing to guide the lines of tear. When the tears are com-
d, a relatively large opening 37 is formed through
h the enclosure is readily removed (FIG. 2).

If the claims are not fully met by the form of the invention shown in FIGS. 7 to 11, a revised form of the invention is formed from a blank 37 having a line of fold 38, providing a front panel 39 and a back panel 40. In this form the window opening 41 in the front panel 39 is parallel with the fold 38. The side edge 42 of panel 39 extends beyond the edge 43 of the panel 40. The opposite side of the panel 39 has spaced apart extensions 44 and 45, to provide a recess 46 therebetween. Substantial alignment with the window opening 41, covering the window opening 41 on the inside face of blank is a transparent patch 48 secured about the window opening 41 by an adhesive 47, and which patch has a length to project over the recess 46 to provide a portion 49.

ie panel 40 has an extension 50 to overlie the tab on 49 when the panel 40 is folded on the fold line. The margin of the panel 40 extending along the edge is sealed to the panel 39 by a stripe of adhesive 51. The panel 40 is of less depth than the panel 39, so that edge 52 terminates short of the edge 53 of the panel.

39 to provide a margin 54 (FIGS. 8 and 11) to cooperate with the exposed faces 55 and 56 of the extensions 44 and 45 and the marginal face 57 that lies between the edges 42 and 43 in accommodating paste or other adhesive when the paste is spread over the outer face 61 of the panel 40.

In this form of the invention, the seam provided by the adhesive 51 and the fold 38 provides the closed sides of the pocket. Thus the construction is simplified through elimination of the flap 6 of the first described form of the invention. Otherwise, the construction follows that of the first described form of the invention.

The enclosure 58 is placed in the pocket 59 between the front and back panels through the free edges thereof until it seats in the fold 38 and the seam that is effected by the adhesive 51. In this position the enclosure 58, which is outlined in dotted lines, FIG. 8, is completely protected by the panel 49.

In applying the label pocket to a mailing piece 60, the surface 61 of the panel 40 and the portions of the panel 39 that project beyond the edges thereof are coated with a paste or other adhesive. The label pocket is then placed upon the mailing piece 60 and pressed in position, as shown in FIG. 9. Or, like in the first form, the paste may be applied to the face of the mailing piece and the label pocket pressed upon the wet paste.

The enclosure 58 is removed in the manner described in the first form of the invention. The loose tab 49 is gripped between the thumb and forefinger and pulled upwardly through the recess 46 so that the slits 18 and 19 start tears of the front panel 39 and which continue along the side edges of the window patch 48 as the tab 49 is pulled across the window opening.

What we claim and desire to secure by Letters Patent is:

- 5 1. A label pocket for application to a mailing piece and
the like, said label pocket including
upper and lower generally rectangular panels having
two side edges thereof interconnected to provide a
pocket between said panels and open at the other
two side edges for insertion of an enclosure into said
pocket,
the upper of said panels having
marginal portions at the open edges thereof projecting
over corresponding edges of the lower panel to pro-
vide faces cooperating with the under face of the
lower panel for closing said insert opening when said
faces are secured to a mailing piece,
a recess in one of the projecting marginal portions of
the upper panel,
a patch inside the pocket having an end thereof ex-
tending freely into said recess, and
adhesive between said patch and said upper panel to
seal the patch to the upper panel,
said free end of the patch providing a tab for grasping
and pulling the patch in a reverse direction over the
upper panel for producing lines of tear in the upper
panel guided by side edges of said patch to produce
a removal opening in the upper panel at a point
from the recess through which an enclosure is re-
moved from the pocket after the label pocket has
been applied to the mailing piece.

2. A label pocket for application to a mailing piece and
the like, said label pocket including
upper and lower generally rectangular panels having
two side edges thereof interconnected to provide a
pocket between said panels and open at the other
two side edges for insertion of an enclosure into said
pocket,
the upper of said panels having
marginal portions at the open edges thereof projecting
over corresponding edges of the lower panel to pro-
vide faces cooperating with the under face of the
lower panel for closing said insert opening when
said faces are secured to a mailing piece by an ad-
hesive.

a recess in one of the projecting marginal edges, a patch inside of the pocket, and an adhesive securing said patch to the upper panel, said patch having an end thereof extending into said recess to provide a tab for pulling the patch in a reverse direction over the upper panel for producing lines of tear in the upper panel guided by side edges of said patch to produce a removal opening in the upper panel for removal of an enclosure from said pocket after the label pocket is applied to the mailing piece, 10 and said lower panel having an extension underlying the recess for protecting the pull tab from the adhesive used in applying the label pocket to the mailing piece.

3. A label pocket for application to a mailing piece and the like, said label pocket including upper and lower generally rectangular panels having two side edges thereof interconnected to provide a pocket between said panels and open at the other two side edges for insertion of an enclosure into said pocket, 15 the upper of said panels having marginal portions at the open edges thereof projecting over corresponding edges of the lower panel to provide faces cooperating with the under face of the lower panel for closing said insert opening when said faces are secured to a mailing piece upon application of the label pocket, 20 a window opening in the upper panel, a recess in one of the projecting marginal edges of the upper panel in alignment with the window opening, and a patch capable of being seen through covering the window opening from the inside of the pocket and 25 having an end thereof extending into said recess to provide a free tab for grasping and pulling the patch in a reverse direction over the window opening for producing lines of tear in the upper panel guided by side edges of said patch when an enclosure is to be removed after application of the label pocket. 30

4. A label pocket for application to a mailing piece and the like to carry an enclosure, said label pocket including upper and lower generally rectangular panels interconnected along one of their edges by an integral fold, 45 the upper of said panels having marginal portions at other edges thereof projecting over corresponding edges of the lower panel to provide faces cooperating with the under face of the lower panel for sealing contact with a face of a mailing piece by means of an adhesive when the label pocket is to be applied, 50 means connecting said panels together at one end of the fold to cooperate with said fold in closing two sides of a pocket between said panels and forming an angular seat for an enclosure to be inserted in said pocket, a window opening for exposing an address carried on the enclosure, 60 a recess in one of the projecting marginal edges and aligned with the window opening, and a patch capable of being seen through covering the window opening from the inside and having an end thereof extending into said recess to provide a tab for grasping and pulling the patch in a direction over the window opening for causing side edges of the patch to produce guided lines of tear across the upper panel when an enclosure is to be removed after application of the label pocket. 65

5. A label pocket for application to a mailing piece and the like as described in claim 4, and including an extension on the lower panel underlying the recess

to protect the tab from contact with adhesive while the label pocket is applied. 6

6. A label pocket adapted to be pasted to a mail piece for containing an enclosure, said label pocket comprising upper and lower panels providing a pocket therebetween, a patch extending within the pocket and having a loose end portion projecting from the pocket, adhesive connecting the portion of the patch with said pocket to the inner face of the upper panel, and said lower panel having a portion underlying said loose end portion of the patch for protecting the loose end portion of the patch from paste used in applying the label pocket to the mailing piece, whereby said loose end portion remains loose and provides a pull adapted to be pulled reversely over the upper panel for tearing the upper panel in providing an opening for said pocket when removing the enclosure. 7. A label pocket adapted to be pasted to a mail piece for containing an enclosure, said label pocket comprising an upper panel having a window opening and a recess from the window opening and located in marginal edge of said upper panel substantially aligning registry with the window opening, a transparent patch covering the window opening the under face of the upper panel and having an end portion extending loosely into the recess of the upper panel, adhesive connecting marginal edges of the portion of the patch that covers the window opening to under face of the upper panel, and a lower panel having a portion extending across recess of the upper panel and underlying said loose end portion of the patch to protect said loose end portion from paste used in securing said label pocket, whereby said loose end portion provides a pull adapted to be pulled from said recess and reversely over the upper panel for tearing through the upper panel in providing an opening for said panel when removing the enclosure. 8. A label pocket adapted to be pasted to a mail piece for containing an enclosure, said label pocket comprising an upper panel having a window opening therein, a lower panel fixed to the upper panel to provide the between a pocket for an enclosure having an addendum to appear in the window opening, a transparent patch covering the window opening the inner face side of the upper panel and having a loose end portion projecting from the pocket, adhesive connecting marginal edges of the patch with marginal edges of the upper panel along the window opening, and said lower panel having a portion underlying said loose end portion of the patch for protecting the loose end portion of the patch from paste used in applying the label pocket to the mailing piece, whereby said loose end portion remains loose and provides a pull adapted to be pulled reversely over the window opening for tearing the upper panel along said adhesive in providing an opening in said pocket when removing the enclosure.
